UNITED STATES PATENT OFFICE.

HYMEN ROSENBAUM, OF BOSTON, MASSACHUSETTS.

HEAD-COVERING.

1,182,210.

Specification of Letters Patent.

Patented May 9, 1916.

Application filed December 15, 1915. Serial No. 66,910.

To all whom it may concern:

Be it known that I, HYMEN ROSENBAUM, a subject of the Czar of Russia, residing at Boston, in the county of Suffolk and State 5 of Massachusetts, have invented new and useful Improvements in Head-Coverings, of which the following is a specification.

This invention relates to improvements in head coverings, especially though not exclusively, adapted for the use of automobilists.

The object of the invention is to provide a neat, comfortable covering, provided with means for shielding the eyes of the wearer 15 from over-strong rays of light, said covering being also provided with means for protecting the eyes from dust and wind.

Another object of the invention is to provide means for retaining a veil in place on 20 said head coverings.

The invention consists in the combination and arrangement of parts set forth in the following specification and particularly pointed out in the appended claims.

25 Referring to the drawings: Figure 1 is a side elevation of a head covering embodying my invention, illustrating the means for shielding the eyes of the wearer from over-strong rays of light in its operative position. A veil is also shown in connection with said covering. Fig. 2 is a side elevation similar to Fig. 1 with the light shield thrown back and the wind and dust shield in its operative position. Fig. 3 is a side 35 elevation of a modified form of covering.

Like numerals refer to like parts in all views of the drawings.

In the drawings, 5 is a cap or main portion of the head covering which is preferably constructed to entirely cover the hair of the wearer. The edge of the cap portion 5 of said covering is contracted by a band 6 which preferably extends entirely there-around, the rear portion 7 of said band 45 being provided with an elastic tape permitting said band to be readily adjusted to different sizes of heads. To the fore part of the band 6 is secured a vizor 8 formed of transparent material preferably celluloid, 50 the widest portion of said vizor being at the front, from whence the same gradually narrows until it finally disappears in the band 6, at points 9 in the vicinity of the ears of the wearer of the covering. A strap 10 is 55 formed preferably as a part of the vizor 8 adjacent each rear portion and at the

forward edge of said vizor, said straps being arranged to be bent upwardly from the outer edge of the vizor 8, and the upper ends of said straps are made fast to the body or cap portion of said covering, preferably by cords 11, looped through eyelets 12 set into said straps, and through corresponding holes in the cap 5. The straps 10, when attached to the cap, form loops 13 60 adapted to receive the ends of a veil 15, the main part of said veil extending over the vizor 8 and adapted to be drawn down over the face of the wearer as illustrated in the drawings. The ends 14 of said veil extend 65 downwardly from the loops 13 beneath the chin of the wearer at which point they may be tied together.

In addition to forming loops for keeping the veil in place, the straps 10 constitute 70 supports for the vizor 8 retaining said vizor in its proper shape and position. As hereinbefore stated, the vizor 8 is formed preferably in two parts, one part being of transparent celluloid permitting the same to be 75 drawn down over the face of the wearer to intersect the line of vision and thus form a protection for the eyes from dust and wind. The other part which constitutes a 80 flap or supplementary vizor 16 of substantially opaque material is preferably formed of the same material as that constituting the cap 5 and is also attached to the fore-part of the cap along the lower edge of the band 6 to which the vizor 8 is also attached. 85 This supplementary vizor is preferably co-extensive with the vizor 8, and is adapted to rest against the upper face thereof and appear as an integral part of said vizor when in such a position. The purpose of 90 said supplementary vizor, is, however, to shut out any over-strong rays of light or sun, or, in other words, shield the eyes from said light, and when employed in this manner said supplementary vizor will be in its 95 lowermost position against the vizor 8 as illustrated in Fig. 1. Under ordinary circumstances, however, the supplementary vizor may not be needed, and therefore said supplementary vizor is adapted to be bent 100 upwardly out of the line of vision of the wearer, as illustrated in Fig. 2, permitting said wearer to look through the celluloid vizor 8 without hindrance. The supplementary vizor 16 may also serve when in its lowermost position as a retainer for the portion 105 of the veil which extends over the vizor 8 110

and to permit the said supplementary vizor to lie more smoothly against said vizor at the points adjacent to the straps 10 said supplementary vizor is terminated at opposite ends thereof as at 17, and will not therefore interfere with said straps during the turning up or down of said supplementary vizor.

In the form illustrated in Fig. 3, straps 10' corresponding to the strap 10 in Figs. 1 and 2 are formed preferably in one piece with the supplementary vizor 16' of the covering, said supplementary vizor being substantially co-extensive with the vizor 8' thereof with the exception of the portion thereof constituting said straps. The ends of the straps 10' are secured, in this form of covering, by eyelets 18 to the cap portion 5' and form thereby loops through 20 which a veil 19 may be passed and retained in position on said covering; said veil passing from said straps around the front of said covering over the supplementary vizor

Having thus described my invention, what 25 I claim and desire by Letters Patent to secure is:

1. A head covering having, in combination, a cap, a vizor therefor in two substantially co-extensive parts, one part being con-

structed of transparent material and the other part of opaque material and straps formed as a part of one of said parts adjacent to the rear portions thereof constructed and arranged to be bent upwardly and attached to said cap to form loops adapted to hold a veil and to reinforce that portion of said vizor of which said straps form a part.

2. A head covering having, in combination, a cap, a vizor therefor in two substantially co-extensive parts, one part being constructed of transparent material and the other part of opaque material, and straps formed in one piece with said opaque material adjacent to the rear portions thereof, 40 constructed and arranged to be bent upwardly and attached to said cap to form loops adapted to hold a veil and to reinforce that portion of said vizor of which said straps form a part.

In testimony whereof I have hereunto set my hand in presence of two subscribing witnesses.

HYMEN ROSENBAUM.

Witnesses:

SYDNEY E. TAFT,
HATTIE E. STRATTON.
